UNITED STATES PATENT OFFICE.

FRANK SIMON CORMIER, OF MONCTON, CANADA.

PROPELLER-GOVERNOR.

SPECIFICATION forming part of Letters Patent No. 678,228, dated July 9, 1901.

Application filed November 16, 1900. Serial No. 36,722. (No model.)

To all whom it may concern:

Be it known that I, FRANK SIMON CORMIER, a subject of the Queen of Great Britain, and a resident of Moncton, in the Province of New Brunswick and Dominion of Canada, have invented a new and Improved Propeller-Governor, of which the following is a full, clear, and exact description.

This invention relates to improvements in governors for propellers of steamships; and the object is to provide a governor of simple construction and automatically controlled to prevent racing of the propeller-shaft when the propeller-wheel rises out of the water.

I will describe a propeller-governor embodying my invention and then point out the novel features in the appended claims.

Reference is to be had to the accompanying drawings, forming a part of this specification, in which similar characters of reference indicate corresponding parts in all the figures.

Figure 1 is a sectional elevation showing a governor embodying my invention as applied to a vessel. Fig. 2 is a section on the line *xx* of Fig. 1; Fig. 3 is a section similar to Fig. 2, showing the parts in a different position. Fig. 4 is a partial section and partial elevation of a controlling-valve employed. Fig. 5 is a detail to show the inlet and exhaust of a working cylinder.

Referring to the drawings, 1 designates a propeller-shaft on which is the usual propeller-wheel 2. Connected to the shaft 1, within the hull of the vessel, is a brake-wheel 3, preferably consisting of sections bolted together, as indicated in the drawings, so that it may be readily applied to the shaft without removing the same. Coacting with the brake-wheel 3 are brake-shoes 4 5, which are respectively pivoted to brake-levers 6, having rocking bearings at their lower ends in boxes 7. Brake-rods 8 connect the upper ends of the levers 6 to oppositely-disposed arms 9 and 10 of an actuating-lever 11. The brake-rods 8 extend through sleeves or boxes 12, having rocking connection with the upper ends of the levers 6, and nuts are engaged with screw-threaded portions of the rods at opposite sides of said sleeves. By this means the rods 50 may be adjusted relatively to the levers 6 to adjust the bearing of the brake-shoes on the brake-wheel. The brake-shoes, as hereshown,

consist of strips of wood or similar material seated in a metal casing attached to the brake-levers.

55

The upper end of the operating-lever 11 connects with a piston-rod 13, which extends from a piston 14, operating in a cylinder 15. The piston 14 is moved in one direction by means of a spring 16, bearing at one end 60 against the piston and at the other end against the head of the cylinder, and it is moved in the opposite direction by means of steam or other suitable motive agent. This motive agent passes to the cylinder through pipes 17 65 17^a, and exhaust-pipes 18 and 18^a lead from said cylinder. Communication is provided between the pipes 17 17^a and pipes 18 18^a by a valve-casing 20, and it will be noted that the pipes 17^a and 18 are respectively on a 70 higher level than the pipes 17 and 18^a. The inlet and exhaust are controlled by a piston-valve 19, operating in the valve-casing 20. This piston-valve controls the passage of the motive agent through the pipes 17 17^a and 75 controls the exhaust through the pipes 18 18^a.

An oil-cup 23 is arranged on the upper end of the valve-casing and communicates with the interior thereof. The upper end or head of the valve 19 is provided with an opening 80 24, in which a valve 25 operates. When the valve 19 moves in one direction, this valve 25 will be sufficiently opened to permit oil to pass through the opening 24 and thence 85 through the pipe 17^a into the cylinder to lubricate the piston, and to prevent the forming of air-cushions at the ends of the valve-heads communication is provided between the two ends of the casing by a pipe 21.

Supported at the stern of the vessel and 90 extending below the same is a float-casing 26, which is entirely closed, excepting that it is provided with a port 27 at its lower end through which water may flow into and out of the float-casing. Movable in the float-casing 95 is a float 28, which is guided and held from lateral movement by means of a cage 29 within the float-casing. The stem of the float extends upward through the upper end of the casing and connects with one arm of a T-lever 30, pivoted on a bracket 31. From the oppositely-extended arms of the T-lever rods 32 and 33 extend to connections with oppositely-extended arms of a T-lever 34, pivoted

100

on a bracket 35, attached to the valve-casing 20. One arm of this T-lever 34 connects with the stem of the valve 19.

In operation should the stern of the vessel 5 rise to lift the propeller-wheel more or less out of the water, the float 28 will move downward by gravity, the water having run out of the casing 26, and by this downward movement of the float the T-lever 30 will be rocked 10 and, drawing upon the rod 33, will rock the T-lever 34 in such direction as to move the valve 19 downward, opening the passage from the pipe 17 into the cylinder at the rear of the piston. The steam or other motive agent 15 thus admitted will move the piston 14 in the cylinder against the resistance of the spring 16, rocking the lever 11 in such direction as to cause the brake-levers 6 to move toward each other and engaging the brake-shoes with 20 the brake-wheel, thus retarding the rotary movement of the propeller-shaft, or, in other words, preventing its racing while the propeller-wheel is out of the water. As the stern of the vessel moves downward and the propeller-wheel is again submerged water will 25 enter the casing 26 through the port 27, causing the float 28 to rise and operating the parts to move the valve 19 upward, closing the inlet-port to the cylinder and opening the exhaust-port, and then the spring 16 will move the piston in such direction as to move the brake-shoes out of engagement with the brake-wheel, as indicated in Fig. 3.

Having thus described my invention, I 35 claim as new and desire to secure by Letters Patent—

1. A governor for a propeller-shaft, comprising a brake-shoe adapted for engaging with the shaft, a cylinder, a piston for operating in said cylinder, a valve for controlling a motive-agent supply to the cylinder, a connection between the piston and the brake-shoe, and a float for controlling the movements of the valve, substantially as specified.

45 2. A governor for a propeller-shaft, comprising a brake-wheel mounted on the shaft, brake-shoes for engaging with said brake-wheel, levers on which the brake-shoes are mounted, a T-lever having connection with 50 said brake-levers, a cylinder, a piston operating in the cylinder and having connection with said T-lever, a spring for moving the piston in one direction, a motive-agent-supply pipe leading into the cylinder, an exhaust 55 leading from the cylinder, a valve controlling said supply and exhaust, and a float for operating said valve, substantially as specified.

3. A governor for a propeller-shaft, comprising a brake-wheel mounted on the shaft, 60 brake-shoes for engaging with said brake-wheel, a cylinder, a piston operating in said cylinder and having operative connection with the brake-shoes, a motive-agent-supply pipe leading into said cylinder, an exhaust 65 leading from said cylinder, a valve for controlling the supply and exhaust, a float-casing arranged at the stern of the vessel, a T-lever having connection with said float, a T-lever having connection with the stem of the 70 valve, and connections between the opposite arms of said T-levers, substantially as specified.

4. A governor for a propeller-shaft, comprising brake-shoes, a cylinder, a piston operating in said cylinder and having operative connection with the brake-shoes, a motive-agent-supply pipe leading into the cylinder, an exhaust-pipe leading from the cylinder, a piston-valve for controlling said inlet and exhaust, 80 a spring for moving the piston in one direction, a float-casing supported at the stern of the vessel and having a port in its lower portion, a float operating in said casing, a T-lever with which the stem of said 85 float connects, a T-lever with which the stem of the valve connects, guides for the float, and rod connections between said two T-levers, substantially as specified.

5. A governor for a propeller-shaft, comprising brake-shoes adapted for braking connection with the shaft, a cylinder, a piston operating in said cylinder and having connections with the brake-shoes, a motive-agent-supply pipe leading into said cylinder, an exhaust-pipe leading from said cylinder, a valve-casing, 90 a valve operating in said casing for controlling the inlet and exhaust, the said valve having an oil-passage, a valve for controlling said passage, an oil-cup on the valve-casing, and a float for controlling the movements of the inlet and exhaust controlling valve, substantially as specified.

6. A governor for a ship's propeller, comprising a steam-actuated brake mechanism for 105 the propeller-shaft, a float-casing attached to the vessel, and a float in said casing operating to control the movements of the brake, substantially as specified.

In testimony whereof I have signed my name to this specification in the presence of two subscribing witnesses.

FRANK SIMON CORMIER.
